CLAIM

The ornamental design for an operation handle for medical device as shown and described.

DESCRIPTION

1. Operation handle for medical device

1.1 : Perspective

1.2 : Perspective

1.3 : Front

1.4 : Back

1.5 : Left

1.6 : Right

1.7 : Top

1.8 : Bottom

The present design relates to a handle used to manipulate a surgical tool during a vascular intervention procedure.

(Continued)

The broken lines in the drawings are for the purpose of illustrating portions of the operation handle for medical device that form no part of the claimed design.

1 Claim, 8 Drawing Sheets
